UNITED STATES PATENT OFFICE.

GILBERT S. DEY, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

BLOCKING MACHINE.

Application filed November 10, 1919. Serial No. 337,090.

To all whom it may concern:

Be it known that I, GILBERT S. DEY, of Southbridge, in the county of Worcester and State of Massachusetts, have invented certain new and useful Improvements in Blocking Machines, of which the following is a specification. This invention relates to improvements in blocking machines, and has particular reference to a machine adapted for use in the accurate blocking of ophthalmic lenses.

One of the leading objects of the present invention is the provision of a novel and improved construction of machine which will satisfactorily serve to automatically accurately block or position lenses on retaining mounts for subsequent grinding.

A further object of the present invention is the provision of an improved substantially automatically operating blocking machine which shall so mount the lens on its block as to reduce the subsequent grinding operations and the care necessary to be observed in connection with said operations to a minimum.

A further object of the present invention is the provision of novel and improved means for accurately uniformly mounting lenses for grinding.

Other objects and advantages of the improved construction should be readily apparent by reference to the following specification taken in connection with the accompanying drawings, and it will be understood that modifications in the specific details of construction shown and described may be made within the scope of the appended claims without departing from or exceeding the spirit of the invention.

Figure I is a front view of a machine embodying the improvements thereof.

Figure II is a side elevation thereof.

Figure III is a horizontal sectional view taken as on the line III—III of Figure II.

Figure IV is a sectional view on the line IV—IV of Figure III.

Figure V is a detail view illustrating the use of the improved gauge.

Figure VI is a detail view in elevation of the upper part of the machine showing the side thereof opposite to the side shown in Figure II.

In the drawings, in which there is illus-

trated a simply constructed form of the invention, the numeral 1 designates the base of the machine, and rising therefrom is a standard 2, upon which is pivoted the collar 3, which is provided with the bracket arms 4 and 5. The standard 2 is further continued upward and forward terminating in the guide bearing 6, in which is slidably mounted the plunger rod 7 whose movement is controlled as through the handle 8 which serves to reciprocate the plunger 7 through any suitable and well known form of rack and pinion or like mechanism. The plunger 7 is provided at its upper end with a longitudinally adjustable clamp collar 9, which in turn for finer adjustments bears the adjustable set screw 10, the parts 9 and 10 together forming a flange stop to limit the downward movement of the plunger, as desired.

At its lower end the plunger 7 preferably bears the carrier head 11 having the depending annular flange 12 surrounded by the resilient ring or gasket 13, while it may also be provided centrally with the presser flange 14 secured as to the spring 15, allowing the yielding of the member 14 to accommodate itself to various curves. It is to be noted that the lower portion of the head 11 has been shown as hollowed out, as at 16, and connected through suitable hose connections 17 with the valve 18, the hollowed-out portion 16 extending downwardly within the flange 12 of the tool head so that the air may be exhausted from said space through the connection 17.

It is the purpose of this head and the vacuum created therein to automatically grasp and hold a lens blank during certain steps in the operation of blocking the lens and insure of proper positioning of the lens.

To cooperate with the member 11 in positioning a lens there is employed a bracket arm 5 whose construction will be best understood by reference to Figures III and IV, from which it will be seen that the arm 5 is carried by the upper portion of the rotatable collar 3, and is provided with the annular lens receiving surface or table portion 19 and the lens edge engaging members 20 which are radially adjustable as through the set screws 21, and which are raised a sufficient height 105 to contact with the edge of the lens near its

upper face, since at this point the lens edge is ordinarily more accurately shaped or formed than at the lower portion of the edge. The radial adjustment referred to 5 permits of adapting this positioning table to different diameters of lens blanks, the apparatus shown, it will be understood, being illustrated for use in connection with circular lens blanks, but it can be suitably modified 10 as to contacts, supports and the like, when other shapes of lens blanks are to be accommodated, the principles of operation, however, remaining the same.

It will be noted that the collar 3 is provided 15 with a second arm 4 to which is secured the operating handle 22 for swinging the collar and attached parts about the standard 2, this second arm bearing the vertically adjustable stud 23 secured in adjusted 20 position as by the nuts 24 and having its upper end formed with a cone taper portion 25 to fit the corresponding socket 26 in the lens block 27, the formation of the cone 25 corresponding to that of the spindle on which the lens block is adapted to be subsequently placed for grinding of the lens 28.

In the operation of the improved device the lens 28 preferably suitably warmed, is placed upon the support 19 with its edge in contact 30 with the positioning members 20 which are so adjusted as to exactly centrally lock the blank upon the support 19, the support 19 at the time of positioning the lens or immediately thereafter being swung about the column 2 as a pivot to bring the center of the support 19 in exact alinement with the plunger 7. With the lens in this position the handle 8 is actuated either manually or by a foot treadle to depress the plunger and bring the flanges 12 and 14 of the head 11 into engagement with the upper face of the lens. As the parts are brought into this position the valve 18 is actuated to exhaust the air from the space enclosed by the flange 12 and on account of the seal created by the gasket 13 around the flange 12 sufficient vacuum will be produced to securely hold the lens 28 in position on the tool 11, the plunger being then reversely shifted to lift the lens off the support 19. This operation having been performed the collar 3 is rotated or swung around to bring the stud 23 in alinement with the plunger 7, suitable stops 29 engaging the adjustable contacts 30 on the collar to limit the swinging movement about the standards so that the two members 19 and 23 may be successively brought into correct position. The member 23 bears on it, as it is swung around, the lens block 27, 55 which has preferably been itself heated as by the burners 30' and has had dropped thereon from the pitch dropper 31, a suitable quantity of the pitch or retaining adhesive for blocking the lens. This blocker 60 is preferably so disposed that when the block

27 is placed in position on the stud and the stud swung to the limit of its lateral movement the side of the block will strike the trip 32 of the dropper and cause exactly the required amount of pitch to be deposited in 70 the block, when it will be kept in heated condition and the block itself heated by the burners or flames 30. The parts, as before mentioned, being then swung to bring the stud in alinement with the plunger, the 75 plunger is again depressed when the lens will be forced down against the pitch 33, the plunger being held down until the parts have had an opportunity to satisfactorily unite. To aid in this uniting, if desired, a fluid supply 80 34 having a discharge nozzle portion 35 disposed immediately beneath the conductor 17, may be coupled with the valve 18, which has certain ports controlling the supply and exhaust of air from the space enclosed by the plunger 12, and other ports allowing a small supply of cooling fluid to flow from the nozzle 35 onto the lens in a fine spray to slightly chill the parts so that the glass and pitch will be quickly cooled to adhere together. 85 90

The parts having been thus united the plunger is reversely shifted, the vacuum being cut out to release the lens which will then remain held on the block 27. 95

The foregoing is a brief description of the general operation of the machine. Attention is called to certain specific features in connection therewith, which it is believed can be best appreciated and understood at this point. The first feature to which attention is directed is the operation of the stops 9 and 10, clearly illustrated in Figure II. of the drawings, from which it will be noted that the stop 10 is contacting with the top of the slide bearing 6 when the parts are 100 in blocking position. The purpose of the adjustment of this stop is to control the exact position of the upper surface of the glass with respect to the remaining parts of the lens grinding machine when the lens is being 105 ground. This is of particular importance since it enables the grinding machine to be set in exact desired position for the particular work to be performed, the parts of the grinding machine itself and the tool being standardized and constant and the only variable factor requiring consideration being that of the glass blank itself, since the glass blanks may vary in thickness, the blocks on which the blanks are mounted may also vary, 110 and the height at which the socket fits the grinding machine spindle may also vary due to wear of the several parts so that this is a continual varying factor in the case of lenses blocked in the ordinary way. 115 120 125

In the case of lenses blocked according to the present improvement, however, the cone 25 corresponds to the cone of the grinding machine and the plunger stop 10 is so adjusted that the lower edge of the flange 12 130

will come to rest at a certain definite relation to the cone representing the grinding machine. When the lens block is mounted on the cone, therefore, it occupies the same 5 relationship to the plunger that it will to the spindle of the grinding machine, while as the flange presses down on the upper surface of the glass or surface to be operated upon and brings this surface down a certain 10 prescribed amount, or in other words, to a certain prescribed relation to the tapered cone of the spindle, the glass surface will be in the identical relation when the block is transferred to the grinding machine, the 15 variables of thickness of pitch, fit of block, thickness of glass blank, and the like, all being taken care of through the amount of pitch which is squeezed out from between the block and blank automatically by the 20 machine. The result is that much less skill on the part of the operator carrying on the grinding operation, less constant attention to the work and standardization of the work is rendered possible for the first time 25 through the use of this improved process of blocking which may be carried out as by the machine forming the subject matter of the present application.

A further feature of this improved machine to which attention is directed is the 30 automatic control for the valve 18, the essential being that the valve shall be automatically operated to create the necessary retaining vacuum when the plunger is first 35 brought toward the glass blank on the support 19, that this vacuum will be maintained while the plunger is raised with the blank and while the plunger is brought down to press the blank against the block 40 but the vacuum cut off before the plunger is raised so the glass blank will not be pulled loose from the block at the completion of the blocking operation. This may, of course, be accomplished by a variety of specific 45 mechanism, and what is to be claimed and protected, therefore, is a mechanism for automatically accomplishing the desired result irrespective of the specific details.

In the form of invention illustrated there 50 is shown the valve 18 as provided with the operating handle 36 adapted to be depressed by the pin 37 on the plunger plate 38 which is preferably carried by the adjustable collar 9, since the main point that is desired is that the valve operate in certain relation to the movement of the plunger irrespective of the adjustment of the plunger through the stop. This plate 38 is provided with the transversely extending slot 39 and the transverse slide 40 having the lifting pin 41 projecting forwardly therefrom for engagement with the handle 36 and riding rearwardly in the track or groove 42 formed in the member 6. It will be noted that this groove is of 65 such form that as the plunger plate is raised

the pin will ride first upwardly and then forwardly and out of engagement with the end of the valve operating lever 36, while as the plate is depressed the pin will ride downward clear of the lever until almost to the limit of movement of the plate, when it 70 it will move inward beneath the lever and then on its upper movement will engage and shift the lever and thus the valve in reverse direction from what it is shifted by the pin 75 37. The advantage of this is that in the initial operation of the machine the pin 37 will partially depress the raised valve or lever handle 36 opening the air exhaust line so the vacuum is created engaging the 80 lens blank. Then as the plunger and lens blank are raised the pin 37 will move out of engagement with the lever which will stay in the position of the valve open. In blocking the lens the pin 37 will move downward 85 and again engage and further depress the lever or handle 36 shutting off the vacuum just as the blank is brought into engagement with the pitch 33 and allowing a slow seepage of air into the vacuum space accordingly releasing the grasp on the blank. At 90 this point the pin 41 is beneath the lever and as the plunger is reversely shifted the pin will raise the lever 36 temporarily opening and again closing the vacuum line in the 95 upward movement when the parts are in position for the next series of operations. As has been mentioned, the controlling valve 18 is a double valve, as illustrated, having a portion controlling the air exhaust and a 100 portion the supply of cooling fluid.

In Figure V, there is illustrated an improved gauge for use in setting the machine, said gauge being substantially in the similitude of a lens block having a tapered socket 105 43 adapted to be selectively engaged on the cone 25 or on a similar cone of a grinding machine, said gauge having an upstanding portion 44 corresponding in height to the combined thickness of the ordinary block 27, 110 pitch 33 and lens 28 so that when the gauge is placed in position on the stud 25 the flange 12 of the presser head 11 may be brought down to bear against the gauge and the stop 10 then set so that the flange just bears 115 against the portion 44.

The gauge may then be removed and similarly employed on the grinding machine to which the blocked lenses are transferred and in this way it may be assured that the upper face of the glass when shifted to the grinding machine will be in certain definite relation to the parts of the grinding machine, which relation can be determined by mounting the gauge on the grinding machine and adjusting the grinding machine to 120 correspond thereto.

From the foregoing specification taken in connection with the accompanying drawings, the construction and operation of the 130

improved machine for use in the accurate blocking of ophthalmic lens blanks or the like should be readily understood, and it will be seen that there has been provided a simple and efficient machine for the intended purpose, which operates in a substantially automatic manner to block lenses with the surface to be operated upon in definite relation to the machine in which the blank is to be subsequently ground.

What I claim is:

1. In a machine of the character described, the combination with a plunger, of means for temporarily securing a lens blank on the plunger, means for automatically releasing said temporary securing means to permit the release of the blank, means for supporting a lens block in alignment with the plunger, and means for limiting the movement of the plunger and lens in the direction of the block.

2. A machine of the character described including a standard, a swinging member on the standard having a pair of arms, a lens positioning device carried by one of the arms, and a lens block receiving device carried by the other of the arms, a plunger, the said arms being adapted to be selectively swung into operative relation to the plunger, and means on the plunger for grasping a blank on the lens supporting arm and for shifting the grasped blank to definite position with respect to the block receiving arm.

3. A lens blocking machine comprising a plunger, a lens holder, a lens block holder, means for successively presenting the lens holder, and lens block holder in operative relation to the plunger, means on the plunger for automatically grasping a lens blank when presented by its holder and for automatically releasing the blank.

4. A lens blocking machine comprising a plunger, a lens holder, a lens block holder, means for successively presenting the lens holder, and lens block holder in operative relation to the plunger, means on the plunger for automatically grasping a lens blank when presented by the holder and for automatically releasing the blank, and means for automatically supplying adhesive to the lens block before it is brought into operative relation to the plunger.

5. A machine of the character described, including a base, a plunger supported by the base and a table rotatable on the base, said member having a lens blank supporting portion and a lens block receiving portion adapted to be selectively presented in predetermined position with respect to the plunger through rotation of the table.

6. A machine of the character described, including a base and a member rotatable on the base, said member having a lens blank positioning portion and a lens block receiving portion adapted to be selectively pre-

sented in operative position through rotation of the member, and a plunger carried by the base for cooperation with the said parts when they are in operative position, said plunger having means for grasping a blank from the holder and support the blank while the remaining parts are being shifted.

7. A machine of the character described including a plunger and an oscillatable bracket, having a lens blank positioning device and a lens block holder adapted to be selectively brought into operative relation to the plunger, means for temporarily retaining a lens blank on the plunger, and stops for limiting the oscillation of the bracket to automatically position the parts in proper relation.

8. A machine of the character described including a plunger and an oscillatable bracket, having a lens blank positioning device and a lens block holder adapted to be selectively brought into operative relation to the plunger, means for temporarily retaining a lens blank on the plunger, means for automatically releasing said temporary retaining means to permit the release of the blank, and adjustable stops for limiting the oscillation of the bracket to automatically position the parts in proper relation.

9. A machine of the character described including a plunger and an oscillatable bracket having a lens blank positioning device and a lens block holder adapted to be selectively brought into operative relation to the plunger, means for temporarily retaining a lens blank on the plunger, stops for limiting the oscillation of the bracket to automatically position the parts in proper relation, and means for limiting the movement of the plunger in the direction of the oscillatable bracket.

10. A machine of the character described including a plunger and an oscillatable bracket having a lens blank positioning device and a lens block holder adapted to be selectively brought into operative relation to the plunger, means for temporarily retaining a lens blank on the plunger, means for automatically releasing said temporary retaining means to permit the release of the blank, adjustable stops for limiting the oscillation of the bracket to automatically position the parts in proper relation, and adjustable means for limiting the movement of the plunger in the direction of the oscillatable bracket.

11. A device of the character described, including a plunger having a suction head and an oscillatable bracket having a work positioning portion and a work receiving portion adapted to be selectively placed in alignment with the plunger, means for reciprocating the plunger in the direction of the bracket, whereby the suction head on the plunger may grasp the work from the

positioning device and transfer it to the work receiving device.

12. In a device of the character described, the combination with a stud shaped to 5 simulate a lens grinding machine spindle, including a portion designed to receive a lens block, of means including a plunger for pressing a lens in the direction of the stud, means for temporarily retaining a lens 10 blank on the plunger, means for automatically releasing said temporary retaining means to permit the release of the blank and means for limiting the pressure in the direction of the stud to a predetermined distance from the spindle.

13. A suction head for a lens blocker having a projecting annulus to fit the curve of the lens and press the lens on its block, and a gasket surrounding the annulus to 20 seal the joint between the lens and annulus.

14. A suction head for a lens blocker having a projecting annulus to fit the curve of the lens and press the lens on its block, 25 a gasket surrounding the annulus to seal the joint between the lens and annulus, and means for exhausting the air from the space enclosed by the gasket.

15. A suction head for a lens blocker having a projecting annulus to fit the curve of the lens and press the lens on its block, 30 a gasket surrounding the annulus to seal the joint between the lens and annulus, means for exhausting the air from the space enclosed by the gasket, and a central presser 35 carried by the head for engagement with the center of the lens blank.

16. A machine for the purpose described, including a base, a bracket oscillatable on the 40 base having a lens supporting portion and a lens block supporting portion, means for positioning a lens on the lens supporting portion, and means for transferring a positioned lens from said supporting portion to 45 predetermined relation to the lens block support.

17. A device of the character described including a base, a bracket oscillatable on the base and having a lens block support and

a lens support, a plunger on the base for 50 selective cooperation with the block support or lens support, means for temporarily retaining a lens blank on the plunger and a heater carried by the base and disposed in position to cooperate with the block support 55 when the lens support is in alignment with the plunger.

18. A device of the character described including a base, a bracket oscillatable on the base and having a lens block support and 60 a lens support, a plunger on the base for selective cooperation with the block support or lens support, means for temporarily retaining a lens blank on the plunger, a heater carried by the base and disposed in position to cooperate with the block support 65 when the lens support is in alignment with the plunger, and an adhesive discharge device disposed adjacent the heater.

19. In a machine as set forth, a frame, a 70 plunger mounted thereon, an oscillatory bracket having a lens blank positioning device and a lens block holder to be selectively brought into operative relation to the plunger, and means for temporarily retaining a 75 lens blank on the plunger.

20. In a machine as set forth, a frame, a plunger mounted thereon, an oscillatory bracket having a lens blank positioning device and a lens block holder to be selectively 80 brought into operative relation to the plunger, means for temporarily retaining a lens blank on the plunger, and means for automatically releasing said temporary retaining means to permit the release of the blank. 85

21. In a machine as set forth, the combination with a plunger, of means for temporarily securing the lens blank on the plunger, means for automatically releasing said temporary retaining means, and means for supporting a lens block in alignment with 90 the plunger.

In testimony whereof I have affixed my signature, in presence of two witnesses.

GILBERT S. DEY.
